[57] CLAIM

We claim the ornamental design for linesman test set design, as shown.

DESCRIPTION

FIG. 1 is a perspective view of the linesman test set design, looking toward the top and right sides, with non-ornamental clip and line cord shown in phantom;

FIG. 2 is a top plan view;

FIG. 3 is a bottom plan view;

FIG. 4 is an elevational view of the right side;

FIG. 5 is an elevational view of the left side;

FIG. 6 is an elevational view of the lower end; and,

FIG. 7 is an elevational view of the upper end.
